UNITED STATES PATENT OFFICE.

ROBERT I. JOHNS, OF BROOKLYN, NEW YORK.

PORTABLE HOUSE.

1,296,084.

Specification of Letters Patent.

Patented Mar. 4, 1919.

Original application filed January 2, 1917, Serial No. 140,051. Divided and this application filed August 1, 1917. Serial No. 183,872.

To all whom it may concern:

Be it known that I, ROBERT I. JOHNS, a citizen of the United States of America, and a resident of Brooklyn, Kings county, 5 and State of New York, have invented certain new and useful Improvements in Portable Houses, of which the following is a specification, reference being had to the accompanying drawings, forming a part 10 thereof.

My invention relates to portable or sectional houses, garages, and other buildings.

In my copending application Serial No. 140,051 filed January 2, 1917, of which this 15 application is a division, I have shown and described a portable building which possesses a number of features of special utility and my present invention is particularly concerned with building beams and the 20 structure of the interchangeable sections.

One object of my present invention is to provide an improved portable house structure that shall be so arranged and constructed that it may be packed in a very 25 small compass and economically shipped to great distances.

Another object is to provide a portable house or building structure that shall be composed of a plurality of sections of material size which may readily be interchanged and secured in the complete building so that the building may be transferred short distances from one location to another and at the same time each section being 30 composed of parts which may be entirely disassembled for the purpose of shipping the structure in a very small compass.

In order that my invention may be thoroughly understood I will now proceed to 40 describe the same in the following specification, and then point out the novel features thereof in appended claims.

Referring to the drawings:

Figure 1 is an elevation of a building wall 45 embodying my invention, showing parts of a plurality of adjacent units.

Figs. 2 and 3 are sectional plan views showing the same building section.

Fig. 4 illustrates the nesting of the studs 50 for shipment.

10, 11 and 12 designate units of a building wall. They are identical in size so that they may be interchanged and assembled in any order desired, and they are structurally 55 similar except that the unit 11 is provided

as illustrated, with a window sash 13 whereas the other two units 10 and 12 are blank wall units. The window sash is intended to be representative of any suitable window or door arrangement, my idea being to have 60 the units interchangeable in order that the window or door unit may be placed wherever it is found most convenient or most suitable to have it located.

The section 11, as illustrated, comprises an 65 inner plate or board 14, an outer plate 15 preferably formed of sheet metal, vertical spacing studs 17, and bolts 18. These parts were assembled to constitute a unit which is complete in itself and as clearly explained 70 is interchangeable with other units of the house.

It is nevertheless composed of parts or members which may easily be assembled and taken apart. By this means the structure 75 may be packed in a small amount of space for long distance shipments as for example, from one country to another, or it may be shipped locally from place to place, without taking apart the various units of the 80 building, by merely separating the house into its units.

The outer sheet metal plate 15 of each unit is formed with a bead or channel 19 near each end so that when the two units 85 are brought together the sheet metal plates may overlap with the beads nesting as shown in Fig. 3. This makes the outer covering of the house tight and makes it easy to assemble the units. 90

The wall board or plates of whatever character on the interior of the building, are not overlapped but their abutting edges are covered by a clamping bead or strip 20 which is held in place by bolts 21 which 95 extend through the studs of the building.

The spacing of the studs in the building is such as to accommodate the units. Consequently, the principal building studs may be placed in position before any of the units 100 are erected.

Each of the studs of which the units are composed as well as the main studs of the building to which the units are attached, is preferably formed of sheet metal and has 105 a channel-shape with flaring webs so that the channels may be nested together in compact form for shipment.

It is evident that structural modifications may be effected within the spirit and scope 110

of my invention, and I intend only such limitations as are imposed by the appended claims.

What I claim is:

- 5 1. A portable house comprising a plurality of interchangeable sections, each composed of outer and inner wall plates, spacing studs or beams, detachable means for clamping the parts of the sections together
- 10 and independent means for connecting the sections together.
2. A portable house comprising a plurality of interchangeable sections some of which may be formed to include doors and
- 15 windows and each of the sections comprising inner and outer wall plates, stamped metal

spacing studs of channel-shaped cross-section, and detachable means for holding the parts of each section together and independent means for connecting the sections together.

20

3. A portable house comprising assembled sections of a plurality of parts, each section being constructed to be connected with an adjacent section, means for connecting said sections together, and detachable means independent of the means for connecting the sections for clamping the parts of each section together.

25

In witness whereof, I have hereunto set my hand this 23 day of July, 1917.

ROBERT I. JOHNS.
